UNITED STATES PATENT OFFICE.

HERMAN MENTEN, OF ASTORIA, NEW YORK.

COMBINED COT AND HAMMOCK.

No. 928,317.

Specification of Letters Patent. Patented July 20, 1902.

Application filed May 16, 1902. Serial No. 433,161.

To all whom it may concern:

Be it known that I, HERMAN MENTEN, a citizen of the United States, residing at Astoria, in the county of Queens and State of New York, have invented certain new and useful Improvements in Combined Cots and Hammocks, of which the following is a specification.

This invention relates to a combined cot and hammock and it has for its object the provision in a single structure of a combined cot and hammock so designed that it may be folded into a very small compass for convenience in carrying, and so that it will serve equally well as a cot and as a hammock. To this end, the invention comprises a sheet or web of any suitable fabric, supporting cords extending along the edges of the sheet or web, brace pieces arranged at the ends and sides of the web and a collapsible supporting structure upon which the web and its brace pieces may be secured when it is desired to use the structure as a cot.

The scope of the invention is hereinafter defined in the appended claims, and in the accompanying drawings I have illustrated a structure embodying all of the distinctive features of my invention.

In the drawing: Figure 1. is a perspective view of the structure suspended as a hammock, the folded supporting structure being dispensed with. Fig. 2. is a perspective view of the structure arranged as a cot. Fig. 3. is a perspective view showing the sheet and braces partly folded, preparatory to rolling into a bundle. Fig. 4. is a view of the cot supporting structure collapsed for convenience in carrying. Fig. 5. is a detail view, showing the preferred mode of connecting the side braces or stiffeners provided along the sides of the sheet or web.

Referring now to the drawings by the reference characters which designate corresponding parts in the several views, 1 is the web or sheet of heavy duck or other fabric which supports the occupant of the structure when it is in use. This web or sheet is folded at the edges to present tubular spaces through which are passed the supporting cords or ropes 2, and in which are also arranged side braces or stiffeners 3. The tubular spaces at the side edges of the web are preferably divided into three sections, and the stiffeners 3 at each side of the web or sheet are three in number. These stiffeners

are not rigidly connected but are secured together by means of strips of pigskin 4 or other tough flexible material. These permit the middle portions of the structure to sag when it is in use as a hammock. To permit approximately rigid connection of the side braces when the structure is in use as a cot, a dowel pin or stud 5 is provided in one of the adjacent ends of each of two side braces, and a socket to receive the dowel pin, 6a or stud is formed in the other adjacent end. Spreaders 6 are provided at the ends of the sheet 1 and are supported on the cords 2 by means of screw eyes 7 at the ends of the spreaders. Connection between the spreaders and the sheet is by means of rings or eyes 8, fastened on the ends of the sheet and engaging books 9 on the spreaders.

When the structure is in use as a hammock, the supports are held in the relation shown in the Fig. 1, the sag of the sheet being dependent upon the load upon it and upon the extent to which the dowel pins at the ends of the side pieces are inserted into the corresponding sockets.

When it is desired to use the structure as a cot, the sheet is supported upon a collapsible structure, comprising 4 pairs of pivoted legs 10, and two sets of braces 11 which are universally jointed to the legs, as shown in Fig. 2, to permit the entire supporting structure to be collapsed readily into a small space, as indicated in Fig. 4. At the top of each leg 10 is provided a rounded stud or knob 12 of metal, which is securely attached to the leg by means of any suitable fastening device. These knobs or studs are provided to engage rings 13 provided at the sides of the sheet as shown in Figs. 1 and 2, and the rings 13 are located with due regard to the distribution of weight upon the sheet when the structure is in use. It will be noted that rings are provided at both ends of the middle side braces because the middle section of the sheet carries a greater portion of the load than either of the end sections, and the greatest rigidity of the support is required in this section. Both ends of this section, therefore, are positively supported upon the intermediate legs 10 of the supporting structure, and each of the end sections of the sheet is positively supported only at its extremity by rings engaging the end pairs of legs in the supporting structure. It is to be understood, of course, that when the supporting structure

is properly set and the sheet mounted thereon, the ends of the side braces are brought into such relation that the dowel pins engage the sockets provided therefor, and so 5 insure a substantially continuous rigid side brace at each side of the sheet. The arrangement of the parts when the structure is in use as a cot will be clearly evident from inspection of Fig. 2, the stretchers at the 10 ends of the sheet and supporting cords being then not in use.

The folding cot supporting the structure is illustrated in Fig. 4 and needs no description, this form of supporting structure being well 15 known in the art and not being the subject of any claim of invention in this claim. The folding of the sheet, together with its several side braces and supporting cords for convenience in carrying is plainly indicated 20 in Fig. 3. Preliminary to folding the structure, the spreaders 6 at the ends of the sheet are disengaged therefrom and slid along the supporting cords to a sufficient distance from the sheet to permit them to be laid on 25 the sheet parallel with the side braces at some convenient point as indicated in Fig. 3. The spreaders being detached from the ends of the sheet, it is easy to fold over one end section of the sheet upon the middle section, as 30 shown in Fig. 3 and then to fold over the other end section upon the section already folded. The parts having been brought into this position, the side braces and end pieces may be brought together as a central 35 core and the sheet rolled around them, to form a compact and approximately cylindrical bundle.

From the foregoing description, it will be 40 apparent that the structure forming the present invention may be made light, yet strong; that it possesses the requisite flexibility for convenient use as a hammock, while it may be easily made rigid at the sides to serve satisfactorily as a cot; and that it is 45 of simple design, so that there is but little likelihood of any cords becoming entangled or any difficulty being encountered in setting

up the structure as a cot, or in suspending it for use as a hammock.

Having thus described my invention, what 50 I claim as new, and desire to secure by Letters Patent, is:

1. In a combined cot and hammock, the combination with a sheet, of supporting cords extending longitudinally thereof at the 55 margins, side braces in sections also disposed longitudinally of the sheet at the margins, and spreaders disposed transversely of the sheet at the ends, said spreaders being detachably connected with said sheet and movable along the said cords.

2. In a combined cot and hammock, the combination with a web or sheet, provided along its sides with guideways, of longitudinal supporting cords at the side of the sheet and 65 a plurality of side braces disposed in said guideways, the side braces in each guideway being flexibly connected and provided with interengaging means, whereby the said side braces may be rigidly connected.

3. In a structure of the character described, the combination with a supporting structure comprising a plurality of spaced pairs of legs, of a sheet detachably mounted on said supporting structure and provided 75 along each side with a plurality of separate side braces or stiffeners flexibly connected provided at their ends with means for rigidly connecting them, and rings attached to said side braces for engaging with said supporting 80 structure one pair of side braces being provided with such rings at both ends, and the other side braces being provided with such rings at one end only.

4. In a combined cot and hammock, a 85 sheet provided at the side margins with supporting cords and also having a plurality of side braces or stiffeners for each side margin.

In testimony whereof, I have signed my name in the presence of witnesses:

HERMAN MENTEN.
